Frederick C. Fischer.

UNITED STATES PATENT OFFICE.

HENRY E. PELLETIER, OF NEWARK, NEW JERSEY, ASSIGNOR TO PELLETIER PRODUCTS MFG. CO., INC., OF ELIZABETH, NEW JERSEY, A CORPORATION OF NEW JERSEY.

VALVE.

1,380,737.

Specification of Letters Patent. Patented June 7, 1921.

Application filed March 1, 1920. Serial No. 362,464.

To all whom it may concern:

Be it known that I, HENRY E. PELLETIER, a citizen of the United States, residing in the city of Newark, county of Essex, and 5 State of New Jersey, have invented certain new and useful Improvements in Valves, of which the following is a full, clear, and exact description, such as will enable others skilled in the art to which it pertains to 10 make, construct, and use the same, reference being had to the accompanying drawings, and to numerals of reference marked thereon, forming a part of this specification.

This invention relates to improvements in 15 valves, and it belongs more particularly to that class in which the valve proper has a rotative movement to and from its seat.

The principal object of the invention is to 20 provide a simple and efficient valve of the class specified, in which both the valve proper and its seat are tapered, and in which provision is made whereby mechanically and positively operated means is employed to give the valve proper a quick rotative movement, and whereby automatic grinding of the valve in its seat will take 25 place at every actuation and so maintain a tight seating action and also prevent any foreign matter from lodging in the seat.

30 The invention consists in the peculiar construction, combination and arrangement of parts as hereinafter referred to and claimed; and a practical embodiment of the invention is represented in the accompanying drawing, 35 forming a material part of this specification, and in which:—

Figure 1 is a sectional side elevation of a fragment of a container in which the invention is embodied, the section being taken 40 centrally of the valve.

Fig. 2 is a cross section, taken on the line 2—2 of Fig. 1 looking in the direction indicated by the arrows, and

Fig. 3 is a similar section, taken on the 45 line 3—3 of Fig. 1 looking in the direction indicated by the arrows.

Referring to the parts shown in the drawing, 4 represents a fragment of a cylinder or container adapted to contain fluid under pressure, and 5 the interior thereof.

In the top of the cylinder casing, there is 55 a threaded bore 6, which communicates with a valve chamber 7. Directly below the bore 6, and preferably centrally thereof, a tapering or conical-shaped seat 8 provides com-

munication between the valve chamber and the interior of the cylinder, the valve seat in its tapering course narrowing toward the last-named. From the valve chamber to the outside of the cylinder, there is provided another bore 9, which is an outlet, and into which is screw-threaded a pipe 10 to receive the discharge from the valve chamber. 60

A threaded plug 11 is screwed into the bore 6, and this plug, between its screw- 65 threads and an exterior flange 12, is made with an upwardly tapering portion 13, designed to make tight fit in a correspondingly tapering wall defining the top edge of the bore. The head of the plug is made 70 with flat sides 14, or in other non-circular form, suitable to receive a wrench whereby to turn it.

The plug 11 has an axial bore 15, into 75 which is fitted for both longitudinal and rotative movements, the end of a stem 16, to the lower end of which is secured by a pin 17, a tapering or conical-shaped valve proper 18, designed to make a tight fit in the correspondingly shaped seat 8. About 80 midway the length of the bore 15, at right-angles thereto, two pins 19 are set in the plug 11 in alined relation. As best seen in Fig. 2, the inner rounded ends of these pins project into spiral threads or grooves 20, 85 cut in the surface of the stem 16 in opposite or intercrossing relation. The purpose of this arrangement is to give the valve proper 18 a quick turning action as it moves either to or from its seat. 90

The valve proper is normally urged into tight fit with its seat by a spring 21, which is coiled around the valve stem and which has its opposite ends seated in recesses 22, provided for the purpose in the confronting 95 faces of the plug and the valve proper. When the pressure in the cylinder overcomes the urge of the spring, the valve proper opens in an obvious manner, permitting the excess pressure to escape into the 100 pipe 10.

With the construction shown and described, the valve, under every opening and closing action, will grind on its seat, making a tight closure, and this grinding action 105 will prevent foreign matter from lodging in the seat, and this result is accomplished by reason of the loose connection between the inner ends of the pins 19 and the spiral grooves in the stem 16 whereby some play 110

or lost motion is provided and also because of the less pitch of the threads in the plug 11 as compared with the pitch of the spiral threads or grooves.

5 Experience has demonstrated that the organization above described is a highly efficient one, and while I have shown the preferred embodiment of my present invention, I do not wish to be limited to the exact 10 details of construction shown and described, as obvious modifications thereof, not involving the exercise of invention, may be made by any skilled mechanic, and such departures from what is herein set forth, I 15 consider within the scope and terms of my claims.

Having thus described my invention, what I claim is:—

1. In a valve, a body having a chamber 20 and an outlet therefor, a tapering seat forming an inlet into the chamber, a plug threaded into the body in line with the tapering seat and provided with an axial bore, a valve proper fitting the seat and provided 25 with a stem having moving fit in said bore and spirally grooved in opposite directions, and pins set in the plug and engaging said grooves to give the valve proper quick rotative movement when actuated.

30 2. In a valve, a body having a valve chamber and an outlet therefor, a tapering seat forming an inlet into the chamber, a plug threaded into the body in line with the tapering seat and provided with an axial bore, 35 a valve proper fitting the seat and provided with a stem having moving fit in said bore and spirally grooved in two directions, pins set in the plug and engaging said grooves whereby to give the valve proper quick ro-

tative movement when actuated, and spring 40 means normally holding the valve proper against its seat.

3. The combination with a valve body having a valve chamber and a tapering seat forming an inlet into the chamber, of a plug 45 threaded into the body in line with said seat and provided with an opening, a tapering valve proper fitting the seat and provided with a stem having moving fit in said plug opening and spirally grooved in opposite 50 directions, pins set in the plug and engaging said grooves by which to give the valve quick rotative movement when actuated, and means for normally pressing the valve 55 against its seat.

4. The combination of a container adapted for holding fluid under pressure, a valve chamber provided in the container wall and having a tapering seat forming an inlet from the container into the chamber, a plug 60 threaded into the container wall in line with the tapering seat and having an opening therein, a valve proper fitting the seat and provided with a stem having moving fit in said plug opening and spirally grooved in 65 two directions, pins arranged to engage said grooves to give the valve quick rotative movement when moved to and from its seat, and a spring confined between the plug and valve proper for normally holding the valve 70 against its seat.

This specification signed and witnessed this 25th day of February, 1920.

HENRY E. PELLETIER.
